(57) **CLAIM**

The ornamental design for a cleaning device for nasal cavities as shown and described.

DESCRIPTION

FIG. 1 is a top perspective view of a cleaning device for nasal cavities;

FIG. 2 is a bottom perspective view thereof;

FIG. 3 is a front side elevational view thereof;

FIG. 4 is a top plan view thereof;

FIG. 5 is a bottom plan view thereof; and,

FIG. 6 is top perspective environmental view of the cleaning device for nasal cavities.

A left side elevational view, a right side elevational view, and a rear side elevational view are not shown, as each is identical to the front side elevational view of FIG. 3. In the drawings, the evenly-spaced broken lines show portions of a cleaning device for nasal cavities that form no part of the claim. The dash-dot-dash lines represent the boundary of the claimed design and form no part thereof.
